FUEL INJECTOR NOZZLE

Louis O. French, Milwaukee, Wis.

Application October 16, 1941, Serial No. 415,170

7 Claims. (Cl. 299—107.6)

The spraying of fuel from an ordinary poppet, particularly cone, type check valve has not been found satisfactory because of the uncontrolled unevenness of its discharge and the high rate of increase of discharge area as the valve is opened. Attempts have been made to modify the action of this type of valve by placing a nozzle member in front of the valve, this nozzle member either being of the fixed type embodying one or more small holes in a nozzle plate or being of the movable type embodying an extension of the head of the valve which cooperates with part of the valve casing to control the discharge.

With the fixed type nozzle plate, the holes sometimes become clogged with carbon deposits, and in some instances the metal of the nozzle becomes red hot and the holes lose their original fixed dimensions. Either of the above conditions will interfere with the proper metering and delivery of fuel to the combustion chamber of the engine. Where the head of the valve is provided with a discharge controlling extension, such extension is subjected to the heat of the engine, and due to its heating cannot be too closely associated with the body of the valve without danger of seizing, and the cavities between the extension and the valve body present places for building up carbon deposits that eventually interfere with the free movement of the valve.

The object of the present invention is to provide a spraying means in the valve casing which is not exposed to the direct heat and combustion gases of the engine except only at the time of injection and which is at all other times covered by a check valve which on opening may in some instances form a deflecting surface for fuel sprays issuing through the seat opening from spray openings in the fixed casing of the valve.

A further object of the invention is to provide an outwardly opening check valve type injector in which the stem of the valve cooperates with its guide bore to control the flow of fuel to the delivery opening so that the supply of fuel may be gradually increased as the valve opens and so that the valve may be moved to a position at a distance from its seat before active spraying of the charge starts.

A further object of the invention is to provide a spray nozzle of the outwardly opening check valve type in which the fuel issues through the valve seat, when the valve is open, in the form of visibly segregated finely atomized sprays.

A further object of the invention is to provide a spray nozzle of the outwardly opening check valve type in which the nozzle openings are provided by grooves formed in the end of a separable tubular guide sleeve for the valve and which end may be inclined more or less from a horizontal plane to provide a less or greater angle for the spray jets.

A further object of the invention is to provide

a spray nozzle in which the spray passages are disposed substantially laterally of the valve stem or a circle slightly larger than said stem and at such an angle of inclination that the main part of each spray clears the seat and also passes above the head of the valve in its open position.

A further object of the invention is to provide an arrangement whereby the valve seat member is subjected to the direct cooling action of the jacket water, so that the valve parts will be prevented from overheating.

A further object of the invention is to provide a spray nozzle which is non-dribbling and in which the maintenance of the spray openings is reduced to a minimum since the construction prevents the clogging of these openings from deposits from the combustion chamber or the excessive heating of these openings and since an efficient filtering system will prevent the discharging fuel from clogging these openings.

The invention further consists in the several features hereinafter set forth and more particularly defined by claims at the conclusion hereof.

In the drawing:

Fig. 1 is a vertical sectional view of a device embodying the invention;

Fig. 2 is a sectional view showing the valve in an open position;

Fig. 3 is an end view of the liner member shown in Fig. 2;

Fig. 4 is a detail horizontal sectional view taken on the line 4—4 of Fig. 2;

Fig. 5 is an elevation view of the valve;

Fig. 6 is an elevation view of another liner member, parts broken away and shown in section;

Fig. 7 is an end view of the nozzle member shown in Fig. 6;

Fig. 8 is a vertical sectional view similar to Fig. 1 showing a modified form of the invention;

Fig. 9 is an end view of the liner member shown in Fig. 8.

The fuel injector nozzle and valve includes a valve 10 and a casing which provides the valve guide, the valve seat, and the spraying outlets.

Referring to Figs. 1 to 5, the casing is formed by a main casing part 11 and a sleeve or liner member 12. The part 11 is provided with concentric bores 13 and 14, the upper larger diameter bore 13 being threaded and the lower small bore 14 being plain and terminating in a conically inclined stop end 15 whose smaller diameter is disposed at the upper or inlet end of an outwardly conically inclined valve seat 16.

The sleeve member 12 is threaded to engage the threaded bore 13 and has a reduced lower part 17 slidably fitting the bore 14 and having a conical end 18 seating on the end 15 of the main casing part. The member 12 has a centrally disposed valve guide bore 19 and a flat surface 20 at the outer end of this bore and end 18. The upper end of the bore 19 communicates with a wrench

socket cavity 21 similar to that used on a hollow head set screw.

The conical end 18 is provided with a plurality (four or five) equally spaced spray grooves 22 of relatively shallow depth to form with the end wall 18 a series of fine fuel passages, which are laterally offset from the guide bore 19 and conveniently formed tangent to the outer circle bounding the surface 20 and are also inclined outwardly so that the bulk of the spray issuing therefrom will clear the seat 16 and also pass clear of the head of the valve 10 in its open position. These passages are supplied with fuel from a space outside the guide bore 19 by providing flats 23 on the part 17 connecting said grooves 22 with an annular recess 24 spaced lengthwise from the seat and connected with the bore 19 by one or more radial passages 25. The ends of the spray grooves 22 terminate at the surface portion 20, and when the sleeve is screwed into place in the main casting part 11, this portion 20 is disposed at or adjacent the inlet end of the valve seat 16.

The discharge valve 10 has an ordinary conical head 26 seating on the seat provided by the seat portion 16 and a stem 27 which is slidably mounted in the bore 19 and is grooved to cooperate therewith to control the flow of fuel to the spray grooves 22. As shown, the stem 27 has an annular conically inclined fuel inlet groove 28. The upper deeper portion of this groove is connected with the socket 21 by a series of flats 29 formed on said stem. The portion 30 of the stem between the groove 28 and the head of the valve forms a plain piston which is preferably closely fitted to the bore 19, thereby preventing at all times any substantial amount of fuel passing directly along the stem from the groove 28 to the head of the valve and thus diverting the fuel from said stem to the passages 25 connected with the spray grooves 22 spaced from said stem.

A coiled spring 31 mounted in the socket 21 surrounds the upper part of the stem 27 and is held in tensioned engagement with the valve by a nut 32 in threaded engagement with said stem and exerting a certain predetermined compression force on said spring 31.

The casing part 11 is shown as threaded to receive a cap 33 having an opening 34 for a suitable fuel supply pipe though it will be noted that this valve structure may be used as the discharge valve of a unit injector.

When the valve 10 is in closed position, the lower end of the groove 28 preferably has a lapped relation, for example, one-thirty-second to one-sixteenth of an inch, relative to the passages 25 connected with the spray grooves with the result that the valve 10 is, during the pressure stroke of the injection pump, first moved outwardly against the pressure of the spring 31 until the groove 28 registers with said passages 25 and the valve head is spaced from its seat at which time the fuel under pressure then flows from the groove 28 to passages 25, recess 24, flats 23, and through the spray grooves 22 from which it issues in fine streams as indicated by the arrow in Fig. 2 in the form of widely divergent finely atomized sprays which make this form of nozzle suitable for distributing fuel into a relatively flat head form of engine combustion chamber.

Furthermore, with the inclined groove 28 the flow of fuel to the spray grooves 21 is gradually increased as the valve 10 moves outwardly to the limit of its travel which may be determined by any suitable stop means, as for example, the engagement of the nut 32 with the top of the liner 12.

It is also to be noted that the width of the seat 16 may in practice be made relatively small, for example, from one-sixty-fourth to one-thirty-second of an inch so that the distance the valve head 26 has to move before it clears the seat 16 and the exposed end of the valve casing is small. The small flat surface 20 permits the grooves 22 to extend into this surface clear of the inner diameter of the seat 16.

Another form of liner which gives somewhat different spray characteristics is the liner 12' shown in Figs. 6 and 7. This liner is identical with the first described form except at the outer end of the valve guide bore 19 a conically inclined surface 34' of the same general slope as that of the seat 16 is provided and the spray grooves 22' generally similar to the grooves 22, terminate at the outer portion of this surface 34'. The valve head for this liner may project in over the inclined surface 34' in the closed position of the valve, but this surface is not relied upon as a sealing surface. It has been found that the sprays produced by such a form are not as divergent as the first described form, and in some instances these sprays striking the head of the valve change the direction of the fuel particles.

Where direct impact of the sprays on the valve is relied upon for fuel distribution, the form shown in Figs. 8 and 9 may be used. The casing part 11 for this form is the same as the first form, and the liner 35 is of the same general form as the liner 12' except that the spray grooves 36 are straight radially disposed notches formed in the end 18' and discharging into the conically inclined end surface 34'' which is similar to the surface 34' and similarly associated with the head 26 of the valve 10.

It is to be noted that the conical head 26 of the valve 10 for the liners 12' and 35 preferably extends to the stem diameter to keep down the dead oil space beyond the grooves.

With the form of Fig. 8 when the fuel pressure acts to open and move the valve 10 to a position clear of the seat 16, the jets from the grooves 36 pass down through the valve seat opening and strike the inclined seating surface of the valve 10 and are deflected generally radially therefrom, the angle of dispersion of these jets varying with the angular incline of the end 15 and to some extent with the angular incline of the head 26. While the amount of variance of the angle of the head 26 may be through 15 or 20 degrees, the angularity of the end 15 may be varied through widely varying limits to provide different spray distribution patterns.

For cooling the valve the casing part 11 has direct threaded engagement at its reduced threaded end 37 with a threaded opening in the wall 38 of the cylinder or cylinder head of the internal combustion engine, and the walls of this casing are preferably directly exposed to the cooling water in the engine jacket space 39 whose outer wall 40 is bored out to fit the rounded upper portion 41 of the part 11 and is also recessed and threaded at 42 to receive a packing gland nut 43 which compresses the packing 44 to form a leak-tight joint at the upper end of the nozzle. At its lower end a gas seal is effected by a suitable soft metal ring 45 clamped between the part 11 and the shoulder at the upper part of the threaded opening in the wall 38. Thus the part 11 which has the valve seat formed in it is in direct contact with the cooled engine walls and the cooling medium itself, so that this will keep this part cool and prevent serious dis-

tortion of the valve seat and will keep the valve head in contact therewith cool. The liner part 12, 33, or 35, being completely encased in the part 11, will be cooled thereby as well as by the fuel passing through the liner.

I desire it to be understood that this invention is not to be limited to any particular form or arrangement of parts except in so far as such limitations are included in the claims.

What I claim as my invention is:

1. In a fuel injection nozzle, the combination of a casing having a fuel passage with a valve seat at one end and including a liner member for a part of said passage having spray grooves in one end opening into the outer portion of an annular flat surface on this end of said liner member adjacent the inlet end of said seat and normal to the axis of the passage through said member, an outwardly opening fuel-pressure-operated check valve mounted in said passage and controlling the flow of fuel past said seat and having a stem extending through said liner member, said spray grooves extending substantially tangentially of the periphery of said annular surface into which they open and so inclining outwardly as to direct fuel sprays therefrom between the end of the casing and the head of the valve in its open position.

2. In a fuel injection nozzle, the combination of a casing having a fuel passage with a valve seat at one end, an outwardly opening fuel-pressure-operated check valve in said fuel passage controlling the flow of fuel past said seat and having a stem, said fuel passage including a plurality of fuel spray passages arranged in the casing to direct the bulk of the fuel charge laterally of the stem of said valve and outwardly through the space between the seat and the open valve clear of the valve head in a predetermined position, and other valve means so controlled relative to the first said valve as to delay the feeding of fuel to said fuel spray passages until the first said valve is in its predetermined open position.

3. In a fuel injection nozzle, the combination of a casing having a fuel passage with a valve seat at one end, an outwardly opening fuel-pressure-operated poppet check valve mounted in said fuel passage and controlling the flow of fuel past said seat, said fuel passage including a plurality of fuel spray passages disposed in said casing adjacent said seat to discharge their fuel charges through the opening in said seat, and other valve means so controlled relative to the first said valve as to delay the feeding of fuel to said fuel spray passages until the first said valve is in predetermined open position.

4. In a fuel injection nozzle, the combination with a casing having a fuel passage with a valve seat at one end, and an outwardly opening fuel pressure operated check valve mounted in said casing and controlling the flow of fuel past said seat and having a stem extending through a part of said fuel passage, said fuel passage including a guide for the stem of said valve and also including a passage extending through the wall of said guide means which contacts with said stem, and a plurality of fuel spray passages arranged in the casing in laterally spaced relation to the stem of said valve with their inlets communicating with the outlet of said passage through said wall and their outlets adjacent the valve seat and so directed that discharge therefrom substantially clears the valve stem and clears the valve after the valve has been opened a predetermined

amount, said stem being in the form of a piston valve which so cooperates with said passage through the wall of said guide means as to delay the supply of fuel to said spray passages until said valve has been opened said predetermined amount.

5. In a fuel injector nozzle, the combination of a casing having a fuel passage with a valve seat at one end and including a liner member for a part of said passage providing a guide bore for the valve, a passage extending through the wall of said guide bore at some distance back from said seat and spray grooves having their inlets communicating with said passage in said guide bore and their outlets adjacent the valve seat, and an outwardly opening fuel pressure operated check valve controlling the flow of fuel past said seat and having a stem slidably mounted in said guide bore and forming a piston valve which so cooperates with said passage through the wall of said bore as to delay the supply of fuel to said spray passages until said valve has been opened a predetermined amount, said stem substantially filling the lower end of said guide bore in the open position of said valve.

6. In a fuel injection nozzle, the combination of a casing having a fuel passage with a valve seat at one end and including a liner member for a part of said passage providing a guide bore for the valve, a passage extending through the wall of said guide bore at some distance back from said seat, and spray grooves having their inlets communicating with said passage through said guide bore and their outlets adjacent the valve seat, and an outwardly opening fuel pressure operated conically headed check valve mounted in said passage and controlling the flow of fuel past said seat and having a stem slidably mounted in said guide bore and forming a piston valve which so cooperates with said passage through the wall of said bore as to delay the supply of fuel to said spray grooves until said valve has been open a predetermined amount, said stem filling the lower end of said guide bore in the open position of said valve, said grooves disposed adjacent said seat and positioned to discharge the bulk of their fuel charges laterally of and clear of the stem of said valve and the valve and outwardly through the space between the seat and said valve after it has been opened a predetermined amount.

7. In a fuel injection nozzle, the combination of a casing having a fuel passage with a valve seat at one end and a bore, a sleeve member mounted in said bore and having a centrally disposed valve guide bore, a passage extending through the wall of said guide bore at a distance back from said seat and a conically inclined portion at one end of said guide bore provided with spray grooves having their inlets communicating with said passage through said guide bore and their outlets adjacent said valve seat for discharging fuel streams through said seat, and an outwardly opening fuel-pressure-operated conically headed check valve mounted in said passage and controlling the flow of fuel past said seat and having a stem slidably mounted in said guide bore and forming a piston valve having a conically grooved portion adapted to so cooperate with said passage through said guide bore as to delay the supply of fuel to said spray grooves until said valve has been opened a predetermined amount.
